CLAIM

The ornamental design for a lens for a combined vehicle headlight and signal light, substantially as shown and described.

DESCRIPTION

FIG. 1 is a front right side perspective view of a lens for a combined vehicle headlight showing our new design, the automobile being fragmentarily shown in broken lines for illustrative purposes only;
FIG. 2 is a front view thereof on a reduced scale;
FIG. 3 is a top view thereof on a reduced scale;
FIG. 4 is a right side view thereof on a reduced scale;
FIG. 5 is a left side view thereof on a reduced scale;
FIG. 6 is a cross-sectional view thereof taken on line 6—6 of FIG. 2 on a greatly enlarged scale.

FIG. 1.

FIG. 2.

FIG. 3.

FIG. 4.

FIG. 5.

FIG. 6.
